INVENTOR

HOMER D. SMITH

BY Paul H. Hawley,
HIS ATTORNEYS

UNITED STATES PATENT OFFICE.

HOMER D. SMITH, OF LARIMORE, NORTH DAKOTA.

AXLE-BOX FOR VEHICLES.

SPECIFICATION forming part of Letters Patent No. 674,817, dated May 21, 1901.

Application filed July 9, 1900. Serial No. 22,913. (No model.)

To all whom it may concern:

Be it known that I, HOMER D. SMITH, of Larimore, county of Grand Forks, State of North Dakota, have invented certain new and useful Improvements in Axle-Boxes for Vehicles, of which the following is a specification.

My invention relates to devices for use in connection with a vehicle axle box or bushing used between the wheel-hub and the axle-spindle. Heretofore it has been customary to take up the wear between the box and spindle by inserting washers between the collar at the inner end of the spindle and the box. In this way longitudinal movement of the box may be prevented; but the washers tend to throw the box out of its normal position on the spindle and permit dust and dirt to enter between the inner end of the box and the spindle. If the washers are put on the outer end of the spindle, there being on the ordinary axle no holder or guard for more than one, any additional washers will soon be stretched by the box, so that they will slip over over the end of the same, rendering it necessary, in order that the box may be kept tight, to renew the washers every few days. Another objection to the use of washers at the inner end of the box arises from the fact that the axle-box spindle is usually tapered to correspond to a similar tapered surface on the spindle. Consequently when the position of the box on the spindle is changed by the insertion of washers at its inner end the relation between the tapered surfaces will not be maintained and undue lateral movement of the box permitted.

One object therefore of my invention is to provide means for guarding and holding the washers in place on the outer end of the spindle to prevent them from being stretched out of shape or dislodged by the axle-box.

A further object is to provide means for rendering an axle-box dirt and dust proof even after it has been in use several years.

A further object is to provide dust-proof means for taking up the wear and consequent lost motion of the axle-box without changing the original position of the box and its axle-spindle.

The invention consists generally in various constructions and combinations, all as here-

inafter described, and particularly pointed out in the claims.

In the accompanying drawings, forming part of this specification, Figure 1 is a longitudinal sectional view of an axle hub and box embodying my invention. Figs. 2 and 3 are details of the ring interposed between the box and locking-nut. Fig. 4 is a sectional view showing a modified construction of the ring and nut.

In the drawings, 2 represents a wheel-hub, 3 the axle, and 4 the tapered axle-spindle, provided at its inner end with the annular shoulder or rib 5 and the collar 6, having the annular groove 7, wherein a quantity of grease may be placed. 8 represents the axle-box, having its inner surface tapered to correspond with the tapered surface of the shoulder 5 and a flange 10 to overlap the grooved collar 6. A flat washer 11 is usually provided between the shoulder 9 and the collar. As the axle-spindle and the box become worn several washers are usually inserted between the collar 6 and the shoulder 9, and as each additional washer is inserted the box will be moved a corresponding distance nearer the outer end of the spindle and the inner end of the same exposed to the entrance of dust and dirt. To obviate this difficulty, I prefer to provide a ring 12, adapted to fit over the end of the spindle, and between which and the outer end of the box one or more washers 13 may be placed. These washers take up the lost motion occasioned by the wear of the box and spindle and retain the box in its original position on the axle. As the wear on the box and spindle increases it is necessary simply to insert more washers between the ring and the outer end of the box.

The ring 12 is preferably provided with a tapered surface 14, adapted to fit snugly within a flange 15 on the locking-nut 16, so that when the nut is removed from the spindle 95 the ring will slip off with it and render it unnecessary for the operator to remove the ring with the fingers. The ring is also provided with a flange 17, adapted to overlap the end of the box and form a guard or holder for the washers to prevent them from being stretched out of shape and pushed out of their proper position by the axle-box.

Fig. 1 of the drawings represents an axle

box and spindle that are considerably worn, and a recess 18 is shown in the hub, wherein the flange on the nut is adapted to fit before the spindle and box are worn sufficiently to necessitate the insertion of the ring. After the ring has been placed on the spindle the flange 17 will enter the recess, and as the said flange is wider than the flange on the nut I prefer to provide a series of teeth 19 in its edge, which will dig into the hub and form a depression therein of sufficient depth to permit the ring to be inserted over the end of the spindle.

In Fig. 4 I have shown a slight modification of the device, which consists in providing a ring with a series of dowel-pins 20 to fit within holes in the lock-nut 21, that is designed particularly for wagons where the flange 15 is usually omitted. The pins 20 fit snugly within the holes in the nut, so that the ring may be easily removed from the spindle upon the removal of the nut. At the inner end of the axle-box on the shoulder or rib 5 I have shown a thin ring 22, that I prefer to place thereon after the box and shoulder have become worn from use to prevent lateral movement of the box on the spindle. As the wear on the box and spindle increases additional washers may be placed between the ring and box, so that regardless of the length of time the box and axle may have been in use it can be always kept in its original position on the spindle. The ring may, if preferred, be formed integrally with the locking-nut, or the flange provided on the nut may be lengthened to overlap the end of the box regardless of the wear thereon, and a suitable shoulder provided within the flange, between which and the box the washers may be placed. This modification in construction I

regard as one that would be obvious to any one skilled in the art and not a departure from my invention.

Having thus described my invention, I claim as new and desire to secure by Letters Patent—

1. The combination, with an axle-spindle having an annular shoulder or rib near its inner end, of a box provided on said spindle and overlapping said shoulder, and a flat ring adapted to be placed on said spindle over said shoulder or rib to take up the space caused by wear between said rib and box, substantially as described.

2. The combination, with an axle-spindle 45 of a box thereon, a ring 12 adapted to fit over the end of said spindle and having on one side a flange to overlap the interposed washer or washers and the outer end of said box and on the opposite side provided with a 50 tapered flanged surface 14, a locking-nut for the threaded end of said spindle, and a flange 15 provided on said nut and forming a socket to receive the flanged surface 14 and wherein said surface is snugly wedged, for the purpose 55 specified.

3. The combination, with an axle-spindle, of a box thereon, a locking-nut, a ring interposed between said box and said nut and having a flange adapted to overlap the ends of 70 the box and one or more washers placed between said ring and box, and said flange having a toothed or serrated edge to engage the end of the hub, for the purpose specified.

In witness whereof I have hereunto set my hand this 28th day of June, 1900.

HOMER D. SMITH.

In presence of—

A. STONEHOUSE,
O. F. PETERSON.
